APPARATUS FOR CONSTRUCTING
CONCRETE PILES

Joseph H. Thornley, Evanston, Ill.

Application December 14, 1932, Serial No. 647,149

8 Claims. (Cl. 61—73)

The present invention pertains to apparatus for constructing concrete piles of the type wherein the concrete is cast in place in a relatively light tapered shell which has been previously driven 5 into the ground by a tapered driving core. This core substantially fills the light tapered shell and reinforces the same during the driving operation. After the core and shell have been driven down to the desired depth the core is withdrawn 10 from the shell, leaving the latter in the ground. Thereupon, the shell serves as an outer form for excluding water and for retaining the sides of the hole open to receive the concrete, the shell remaining as a permanent part of the finished 15 pile, in the form of a thin metallic sheath encasing the concrete shaft. Since there are as many shells required as there are piles to be cast in place, it follows that it is of extreme importance that these shells be of as low cost as possible, preferably being of relatively light gauge metal.

It has, for many years, been common practice to construct cast in place concrete piles in this particular manner. Such difficulty has been experienced, however, in withdrawing the core from the tapered shell, because of the tendency of the shell to come up with the core. One prior method of freeing the core from the shell has been to make the core of collapsible construction so that it can be reduced in size within the shell to facilitate its removal therefrom. This collapsible construction is, however, objectionable for several reasons, including the high initial cost, the rapid deterioration under the severe blows of the pile driving hammer, and the time lost in making repairs which are so frequently necessitated by the extreme service conditions.

It has also been common practice, for the past twenty years or so, when removing the core from the shell in pile forming apparatus and in steel pipe piles where a heavy shell of steel is used, to attach or anchor the upper end of the shell temporarily to the pile driver leads, as by means of struts or dogs engaging between the upper portion of the shell and the base portions of the leads, or by means of a cable sling wrapped around the upper portion of the shell and anchored to the leads, and thereafter to withdraw the core by taking the hoisting pull of the lifting tackle over the head block in the upper ends of the leads, whereby the reaction of this pulling force is transmitted downwardly through the pile driver leads and through the aforesaid struts, dogs or sling into the upper head portion of the shell, so as to prevent the possibility of the shell being raised with the core.

It has not, in the past, been practicable to use this last described method for removing a core from a light gauge shell because these light shells have relatively small strength against compression stresses and hence if the reaction of pulling the core is applied to the head end of such a shell where it is borne solely by the compression strength of the shell, there is the likelihood of the shell buckling or crumpling under this strain.

The present invention aims generally to provide an improved tapered driving core and associated core removing apparatus which avoids the complications and objections residing in the prior collapsible type of driving core, and which has particular cooperation with the driving of thin shells of light gauge metal in that the core can be withdrawn in a convenient, expeditious manner without distorting the light shell or otherwise subjecting it to stresses which it is not able or adapted to withstand. More specifically, 10 it is one of the objects of the invention to provide apparatus which, in causing separation between the core and shell, will result in the reaction force being borne as a tension stress in the shell. That is to say, the reaction force incident to the upward pulling effort exerted on the core is applied not to the upper end of the shell, but rather to the lower end where it places the entire shell under tension. For example, in the preferred embodiment of the present apparatus, this downward reaction force is transmitted through a long bar or push rod constituting the inner portion of the core, which push rod applies the reaction force to the lower closed 15 end of the shell. By thus applying this downward pushing force to the lower portion of the shell, the entire length of the shell is maintained 20 under tension stress during the separating operation, i. e., the reaction force is borne solely as a tension stress in the shell. While these light 25 shells have a relatively low load bearing value in compression, they have an extremely high load bearing value in tension, and hence they are well able to bear all of the reaction of the separating force, incident to freeing the friction grip 30 of the core therein, when this reaction force is 35 sustained as a tension in the shell.

Other objects and advantages of the invention will appear from the following detail description of a preferred embodiment thereof. In 40 the accompanying drawings illustrating such embodiment:—

Figure 1 is a view of the apparatus as seen 45 from the front of the pile driver leads, the light 50

shell and the improved construction of core being fragmentarily illustrated in section;

Figure 2 is a fragmentary vertical sectional view taken approximately on the plane of the line 2—2 of Figure 1; and

Figures 3 and 4 are views similar to Figures 1 and 2, illustrating a modified embodiment or application of the invention.

The light metallic shell, within which the pile 10 is subsequently formed, is indicated at 8. In the case of a relatively long pile, this shell may consist of a plurality of connected sections. The driving core 9, 10 which fits within this shell is of two-piece construction, comprising the tapered outer body portion 9 and the reciprocable inner thrusting member 10. The shell 8 and the body portion 9 of the core preferably have substantially the same degree of taper throughout their contacting portions. The lower end of the shell 8 is preferably closed, and may have a rounded or square ended extremity 11, as desired. A driving end head or button 12 is suitably secured to the lower end of the inner thrusting member 10 for transmitting the driving force to the base end of the shell and also for transmitting thereto the downward pressure of the thrust member 10 in the separating operation. The upper end of the shell 8 may, if desired, be reinforced by an external annular flange 13.

The upper end of the core body 9 carries a driving head 14. The thrusting element 10 extends substantially the entire length of the core body 9. Said thrusting element is suitably guided for sliding motion in the core, and can be projected from the lower end 15 of the core body, substantially as illustrated in Figure 1. The core body can be of solid construction, with an appropriate bore therein for the thrust member 10, or it can be of relatively heavy hollow construction provided with suitable spiders or bearing hubs disposed at longitudinally spaced points in the core body for guiding the rod member 10. The latter construction is shown, and the spaced spiders or bearing hubs are indicated at 16.

In the preferred construction, the thrusting element 10 serves as a driving element as well as a separating element. Accordingly, this thrusting element is made of heavy construction, preferably consisting of a heavy pipe. During the driving operation the upper end of this pipe abuts against the lower side of the driving head 14 and the end plug 12 of said pipe abuts against the closed bottom of the shell 8. This pipe sustains the major portion of the driving force, and it might be constructed to sustain all of the driving force. Where the core body 9 is to sustain some of the driving force, the end 15 of said body abuts against the end plug 12 during the driving operation. The bearing supports 16 prevent any sidewise buckling or bending of the pipe 10 during the driving and separating operations. The upper portion of the core body is provided with diametrically opposite vertical slots 17 through 65 which passes a cross yoke or bar 18. The latter is adapted to transmit the downward reaction pressure to the thrusting pipe 10 during the separating operation, such cross bar having any suitable connection with the pipe, represented, for example, by an eye or apertured loop portion 19 in the center of the cross bar. This eye or loop portion lies horizontally and the thrusting pipe 10 passes up through the aperture therein. Flanges or collars 21 secured to the pipe engage 75 the top and bottom of the eye or loop portion 19.

After the shell and core have been driven to the desired depth in the ground, the core is released from this driving wedge grip with the shell by applying an upward pulling force on the head 14 and by applying a downward reaction force to the base end of the shell through the thrusting element 10 which then serves as a push rod. The apparatus for exerting these separating forces comprises a series of upper sheaves 24 mounted in an upper sheave block 25, and a co-operating series of lower sheaves 26 mounted in a lower sheave block 27. A cable 28 is reeved successively over these upper and lower sheaves, and has its one end operatively connected with a winch and its other end suitably dead-ended, in a manner which I shall hereinafter describe. The tension transmitted to this cable from the winch exerts an upward pull on the lower sheave block 27 and exerts a downward reaction thrust on the upper sheave block 25. The downward thrust of the upper sheave block 25 is transmitted to the cross bar 18 through the instrumentality of a frame 31. The vertical side rails 31' of this frame have suitable sliding engagement with the leads 32 of the pile driver tower. For example, these side rails 31' may be formed with outwardly facing channel guides for engaging directly over the inner guide surfaces of the leads 32, or they may be formed with other forms of guide surfaces for engaging with supplementary guide surfaces on the leads, separate from the inner surfaces of these leads. The upper sheave block 25 is fixedly secured to the upper cross rail 31" of the frame 31. The lower portions of said side rails 31' have operative connection with the ends of the cross bar 18 in any suitable manner. For example, this attachment may be effected by brackets 33 which are detachably secured to the side rails 31'. The lower portion of each bracket is formed with a semi-cylindrical socket, and a lower attachment clip 33' is formed with a matching semi-cylindrical socket. The ends of the cross bar are mounted in these sockets and each bottom clip 33' is detachably bolted to its upper bracket portion 33 for holding the cross bar in place.

The lower sheave block 27 is operatively connected to transmit an upward pull to the driving head 14 on the upper end of the core. In the preferred arrangement illustrated, this sheave block is operatively connected with said driving head 14 through the instrumentality of the pile driving hammer, generally indicated at 34, although it will be understood that said sheave block 27 might be attached directly to the head 14, during the operation of separating the core from the shell. The hammer unit 34 is adapted to slide vertically within the frame 31, and comprises the upper steam cylinder 35, the lower hammer base 36 and the reciprocating ram 37. Vertical guide rods 38 extend from the cylinder 35 down to the hammer base 36, and the ram 37 is guided for reciprocation along the rods. The impacting end 37' of the ram 37 can be arranged to strike the core head 14, or to strike the hammer base 36, or a member interposed between said impacting end and the core head. The cylinder 35 has outwardly extending side portions 35' and the hammer base 36 has outwardly extending side portions 36', which side portions 35' and 36' may be formed with guide surfaces for sliding contact directly with the inner sides of the frame rails 31', or which side portions may be connected by a sub-frame slidably mounted within the frame 31. In the illustrated construction, 75

the hammer unit 34 with these guide extensions 35', 36' also forms, in effect, an inner frame member or core releasing member guided for vertical movement within the outer frame structure 31. Means are provided for transmitting an upward pull from the hammer base 36 to the core head 14, such being illustrated in the form of links or hooks 41 having operative attachment to the hammer base and to the core head. The range of upward movement of the hammer unit 34 within the frame 31 is limited by the lower ends of the slots 17 engaging the under sides of the cross bar arms 18.

In the operation of driving the shell, the frame 31 with its contained hammer unit 34 is hoisted into the top of the derrick leads 32, with the core 9 and its container push rod 10 depending therefrom. The shell 8 is then lifted into position between the hammer leads 32 and the core 9, 10 is lowered into the shell. Thereupon, the driving operation is performed by the operation of the steam hammer, the blows of the ram 37 driving the core and shell down into the ground. The tied connection between the core head 14 and hammer base 36 may be relied upon to guide the shell and core, or other supplementary guiding means may be arranged to assist in guiding the core and shell in their downward movement.

After the shell has been driven to the desired depth the core is separated therefrom by exerting a tension on the cable 28. The cable may be reeved in various ways so as to exert different separating forces between the core and shell, and so as to combine therewith, if desired, different lifting pressures on the core assembly. That end of the cable which is being wound around the winch, and which may be termed the pulling end, is designated 28a, and the other end of the cable, which may be termed the dead end, is designated 28b. A proper understanding of the invention will be facilitated by first assuming the cable to be reeved as illustrated in Figures 3 and 4, with the dead end 28b tied to an eye 46 or otherwise dead-ended either to the frame 31 or to the lower sheave block 27; and with the pulling end 28a extended directly from the top of one of the upper sheaves 24 in a more or less downward direction to the winch 47. Assuming that the winch exerts a pull of 5000 pounds on the cable, it will be evident that the six strands or spans of cable illustrated as extending between the upper and lower sheaves and between the last lower sheave and the dead end connection 46 will establish a force of approximately 30000 pounds tending to draw the sheave blocks 25 and 27 together. A separating force of 30000 pounds is thus effective tending to separate the core from the shell. With the cable reeved in this arrangement, a positive downward pressure will also be exerted on the core and on the shell, of a magnitude depending more or less on the angle which the pulling end 28a of the cable takes, in extending from the end sheave 24 of the top group downwardly to the winch 47. Assuming this strand of the cable to be substantially vertical, it will be evident that the cable will exert a downward force on the shell and on the core of approximately 5000 pounds. However, notwithstanding this downward force on both the shell and core, the strands of cable extending between the multiple sheave blocks are creating a 30000-pound force tending to separate the core from the shell. Assuming that this separating force is ample to break the static friction of the driving wedge fit between the core and the shell, the core will thereupon move upward-

ly within the shell. After the core has been lifted to a sufficient distance within the shell, where it is exerting no dragging friction on the shell, the hammer unit 34 can be locked in this elevated position within the frame 31 by any suitable locking means, such as by passing pins 48 (Figure 3) through lugs 49, 49' projecting from the frame rails 31' and from the hammer base 36. A separate tackle line 52, also shown in Figure 3, independent of the cable 28, may now be utilized to lift the frame 31 and core 9, 10 up into the hammer leads. This separate line 52 is shown as being dead ended to an eye 53 secured to the top of the slideable frame 31, and passing over the head block 54 in the top of the tower and thence downwardly to any suitable winch or pulling mechanism 47' (Figure 4) on the pile driver platform.

It will be seen that the foregoing arrangement and mode of operation provides means whereby a large separating force is established for breaking the static friction of the driven wedge grip of the core within the shell; also, that it provides means whereby the separating forces introduce no upward pull on the shell, since the reaction of the upward pull on the core is transmitted in a downward direction to the shell through the push rod 10. Entirely aside from the fact that the upward pull on the core is not transmitted as an upward lift on the shell but rather its reaction is transmitted as a downward thrust to the shell, there are other forces involved which transmit a positive downward force to the shell relative to the earth. These are the combined effect of the tension in the pulling end 28a of the cable, plus the weight of the hammer unit 34, frame 31 and core 9, 10. For example, if the downward force in the pulling end 28a of the cable is 5000 pounds and the weight of the hammer unit, frame and core is 10,000 pounds, the combined effect of the through the frame 31, cross arm 18 and push rod 10 two, or 15,000 pounds, is acting downwardly through the frame 31, cross arm 18 and push rod 10 to the base end of the shell. This operating arrangement is therefore of particular advantage in situations where it is desirable to have a heavy downward force effective on the shell during the core releasing operation, separate from and supplementary to the reaction of the core separating force.

In Figures 1 and 2 I have illustrated another preferred operating arrangement. In this arrangement, the secondary cable 52 is dispensed with, and the main cable 28 is extended from the end sheave of the lower group 26 directly up to the head block 54 at the top end of the tower, and thence down to the winch 47. In this arrangement, the compounded reeving of the cable over the upper and lower sheaves 24 and 26 creates, in the same manner previously described, the relatively large separating force which insures the breaking of the static friction between the core and the shell. The reaction of this separating force is, in the same manner, transmitted through the frame 31, cross-bar 18, and thrust pipe 10 down to the base end of the shell. That is to say, if there is a 5000 pound tension in the cable 28 and if there are five strands effective between the upper and lower sheaves, the separating force will be 25000 pounds; if six strands the separating will be 30000 pounds, etc.; and the reaction of each of these forces will be downward on the shell. With reference to the secondary forces active between the shell and the earth, it will be evident that it is only the 5000 pound force in the strand of cable passing upwardly over the head

block 54 that acts upwardly. But this force, relative to the earth, is opposed by the weight of the hammer unit 34, frame 31 and core 9, 10, which, 5 10000 pounds. Hence, there then remains a force of 5000 pounds acting downwardly on the shell relative to the earth.

For simplicity of description, I have shown only 10 a single strand extending up over the head block 54. If the safe limit of tension which can be imposed on this single strand is not equal to the weight of the hammer unit 34, frame 31 and core 9, 10, it will be necessary to extend one or more 15 additional strands between the head end of the tower and the frame or hammer unit to develop the necessary pull to lift the hammer unit, frame and core up into the leads after the static friction of the joint between the core and shell has been broken. According to one practice, the dead 20 end 28b of the cable can be transposed from the eye 45 in the frame 31 to an upper eye 56 in the head end of the tower, after the static friction has been broken and preparatory to raising the apparatus into the tower; and, according to another 25 practice, this dead end 28b may be left permanently connected to the upper eye 56 for both the joint breaking and lifting operations. In the operation 30 of either of these arrangements, after the static friction of the wedge fit is broken, permitting the core to move upwardly in the shell, the further winding in of the cable carries the hammer unit 34 upwardly until the bottom ends of the slots 17 engage the cross yoke 48 and thereafter the hammer unit, frame and core move upwardly into 35 the upper ends of the leads. It will be evident that by increasing the number of upper and lower sheaves 24 and 26, the mechanical advantage of the apparatus can be increased to the point where the tension applied on cable 23 is relatively small, 40 while still exerting a tremendous separating force between the core and shell. This may be utilized to develop extremely large separating forces with a cable or source of power of limited capacity, or may be utilized, during the joint breaking operation, to reduce the lifting tendency of any strand 45 of cable extending up to the head end of the tower.

It will be seen that in each of the preceding 50 embodiments, the reaction force of separating the core from the shell is transmitted through the push rod 10 to the base end of the shell where it establishes a tension in the shell. As previously mentioned, by thus having this reaction force borne in the shell as a tension stress, the shell 55 is better able to withstand this force, even when made of relatively light material, and is better able to withstand the inwardly acting earth pressures, particularly at the instant of separation of the core from the shell. In transmitting said reaction force to the shell it will be noted the rod 60 10 functions in the nature of a stripper or pusher for stripping the shell from the core member 9.

While I have described what I regard to be the 65 preferred apparatus and the preferred method for carrying my invention into effect, nevertheless it will be understood that such are merely exemplary and that numerous modifications, rearrangements, and different steps may be adopted without departing from the essence of the 70 invention. For example, the same inherent features of the invention can be embodied in a construction wherein the outer tapered core element 9, instead of being a single solid unit from end to end, can consist of several sections, like 75 the successive frustums of a long cone, with these

sections connected together successively by lost-motion means such as chains, slotted links or the like, whereby the upper section is first released, then the next lower section and so on, all while the reaction of the upward pulling force exerted on these sections is transmitted through the push rod 10 to the base end of the shell 8. Within the purview of the invention is also included the use of hydraulic apparatus for breaking the friction wedge grip, represented for example by a hydraulic cylinder connected between the top of the cylinder 35 and the top of the frame 31 in lieu of the sheave blocks 25 and 27 and connecting strands of cable.

I claim:—

1. Apparatus of the class described for driving a pile shell into the ground and releasing itself therefrom, comprising a tapered core which is adapted to be inserted into the shell for forcing the same into the ground, said core comprising two parts, namely, a pair of coaxial members relatively slidable with respect to each other for releasing the core from the grip of the shell, and means for producing relative sliding motion between said two parts, comprising two frame members, the first frame member being an open parallel sided frame having its bottom connected to one of said parts for transmitting thrust, the second frame member being a sliding bar guided within the first frame member and being connected to the second of said parts for transmitting tension, and a cable and pulley connecting said two frame members for drawing them towards each other and thereby sliding said coaxial core members with respect to each other for loosening the core from the grip of the shell.

2. Apparatus of the class described for driving a pile shell into the ground and releasing itself therefrom, comprising a tapered core which is adapted to be inserted into the shell for forcing the same into the ground, said core comprising two parts, namely, a pair of coaxial members relatively slidable with respect to each other for releasing the core from the grip of the shell, and means for producing relative sliding motion between said two parts, comprising two frame members, the first frame member being an open parallel sided frame having its bottom connected to one of said parts for transmitting thrust, the second frame member being a sliding bar guided within the first frame member and being connected to the second of said parts for transmitting tension, a pair of vertical ways in which said first frame member is slidably guided, and a cable and pulley connecting said two frame members for drawing them toward each other and thereby sliding said coaxial core members with respect to each other for loosening the core from the grip of the shell.

3. In apparatus of the class described for driving a tapered pile shell into the ground and releasing itself therefrom, the combination of a tapered core and a stripper adapted to be inserted into the shell for driving the latter into the ground, said stripper extending down into the pile shell to adjacent the lower end thereof and adapted to have contact with said shell, said core and said stripper being capable of relative longitudinal movement, and mechanism for releasing the friction grip between said core and said shell after the driving operation comprising an upper member disposed above said core and having pressure transmitting connection with said stripper, a lower member movable substantially vertically relatively to said upper member

and having tension transmitting connection with said core, and block and tackle means connected to said upper and lower members and operative to cause relative converging motion therebetween.

5 4. In apparatus of the class described for driving a tapered pile shell into the ground and releasing itself therefrom, the combination of a tapered driving core adapted to be inserted into the pile shell for driving the latter into the ground, a supporting structure comprising two substantially vertical spaced guide members extending upwardly substantially above said core, a sheave block mounted on the upper portion of said supporting structure, two vertically spaced core releasing members disposed below said sheave block, means establishing a pressure transmitting connection between the upper of said two members and said shell, means establishing a tension transmitting connection between the lower of said two members and said core, pulleys mounted on said members, and a cable reeved over said sheave block and extending down and reeved around said pulleys, said cable being operative to create tension for causing relative converging motion between said members in order to free said core from said shell and being thereafter operative to raise said core and both of said core releasing members upwardly toward said sheave block.

20 5. In apparatus of the class described, the combination of a tapered driving core adapted to be inserted into a tapered pile shell for driving the latter into the ground, and mechanism for withdrawing said core from said shell after the driving operation comprising an upper member disposed substantially above said shell, a stripper operatively connected with said upper member and adapted to bear against said shell, said stripper constituting a pressure transmitting connection between said upper member and said shell, a lower member movable substantially vertically relatively to said upper member and having tension transmitting connection with said core, and rope and pulley means connected to said upper and lower members and operative to cause converging motion therebetween.

25 6. In apparatus of the class described, the combination of a driving core adapted to be inserted into a pile shell for driving the latter into the ground, and mechanism for separating said core from said shell after the driving operation comprising an upper member disposed substantially above said shell and having pressure transmitting connection therewith, a lower member movable substantially vertically relatively to said upper member and having tension transmitting connection with said core, and rope and pulley means connected to said upper and lower members and operative to cause converging motion therebetween.

30 7. In apparatus of the class described, the combination of a driving core adapted to be inserted into a pile shell for driving the latter into the ground, a frame disposed substantially above said shell and having pressure transmitting connection with said shell, a member movable within said frame and having tension transmitting connection with said core, and block and tackle means connected with said frame and with said member for causing relative motion therebetween.

35 8. In apparatus of the class described, the combination of a driving core adapted to be inserted into a pile shell for driving the latter into the ground, a frame disposed substantially above said shell and having pressure transmitting connection with said shell, a member movable within said frame and having tension transmitting connection with said core, and block and tackle means connected with said frame and with said member for causing relative motion therebetween.

JOSEPH H. THORNLEY.
